UNITED STATES PATENT OFFICE.

JOSEPH K. SIERER, OF NEW YORK, N. Y.

DESIGN FOR TILE COVERING FOR FLOORS, WALLS, OR OTHER SURFACES.

SPECIFICATION forming part of Design No. 36,247, dated March 17, 1903.

Application filed October 6, 1902. Serial No. 126,253. Term of patent 14 years.

To all whom it may concern:

Be it known that I, JOSEPH K. SIERER, a citizen of the United States, residing in the city and county of New York, in the State of New York, have invented a new, original, and ornamental Design for Tile Covering for Floors, Walls, or other Surfaces, of which the following is a specification.

My design is illustrated in the accompanying drawing, which shows a number of tiles having a substantially diamond-faced shape, with two notches and two indentations on each tile united to form a floor or other covering, the shading in the drawing being for the purpose of illustrating the outlines of the individual tiles and not for the purpose of indicating color. The marginal tiles are broken away.

The essential feature of my design is the peculiar shape of the tiles composing it, the face of each being substantially diamond-faced, with two projections on adjacent sides of the diamond and three notches or indentations—one indenting the lower point of the diamond and one on each of the adjacent sides which form the upper point of the diamond, each opposite one to the other.

I claim—

The new, original and ornamental design for tile covering for floors, walls or other surfaces substantially as described and shown in the accompanying drawing.

JOSEPH K. SIERER.
